JOHN BLAKE TARR, OF FAIRHAVEN, MASSACHUSETTS.

Letters Patent No. 98,895, dated January 18, 1870; antedated January 15, 1870.

IMPROVEMENT IN LOCOMOTIVE CAR-WHEELS.

The Schedule referred to in these Letters Patent and making part of the same.

To all whom it may concern:

Be it known that I, JOHN BLAKE TARR, of Fairhaven, in the county of Bristol, and State of Massachusetts, have invented a new and improved Locomotive Driving-Wheel; and I do hereby declare that the following is a full, clear, and exact description of the same, reference being had to the accompanying drawing, making a part of this specification, in which—

Figure 1 is a vertical central section through a press and mould adapted for the production of the improved drivers, showing the several parts in the positions which they occupy, while subjecting the metal in the mould to pressure.

Figure 2 is a diametrical section through the upper section of the mould.

Figure 3 is a diametrical section through the intermediate section of the mould.

Figure 4 is a diametrical section through the bottom section of the mould.

Figure 5 is a diametrical section through the mould and its core, when these parts are brought together, ready to receive the melted metal.

Figure 6 is a top view of the upper section of the mould.

Figures 7, 8, 9, 10 show the improved product.

Similar letters of reference indicate corresponding parts in the several figures.

This invention consists in a compressed cast-metal locomotive driving-wheel, produced by subjecting the metal—while in a liquid state and in the mould which gives to it the desired form—to such a degree of pressure as will expel the gases from the metal, and compel it to perfectly fill every part of the mould, and at the same time render the metal homogeneous in density and toughness, and free from pores, flaws, or other imperfections, as will be hereinafter explained.

To enable others skilled in the art to understand my invention, I will describe one practical mode of producing the locomotive-driver.

The wheel to which I have reference is composed of the following parts, to wit, the tread M, the balance O, the web or spokes N or N', the hub p, and the crank s, all of which parts I am enabled, by my process, to produce at one operation of casting and of one solid piece.

The mode in which I have been successful in producing the improved locomotive-drivers consists of three principal parts, J, K, and L, with a central core, H', for producing a hole through the centre or hub p of the wheel.

These sections of mould, as well as the core, are composed in part of metal and in part of a refractory compound. The metal portions are designed to resist the great pressure to which they are subjected during the process of making wheels, and the refractory substance is designed to prevent the surfaces, which give form to the wheels, and which are exposed to intense heat, from adhering to the castings.

The bottom section L of the mould consists of a flat bed-plate, upon which is bolted a ring, as shown in figs. 1, 4, and 5.

Within this ring-portion is the refractory substance g², the upper surface of which is adapted to produce the inner face and a portion of the flange of the wheel. This substance g² is firmly tamped within the ring, upon a pattern of proper form, before the bottom-plate is secured to the ring.

The intermediate section K of the mould is composed of a cylindrical ring and a flange ring, f, and a refractory lining, g¹, which latter is intended to produce the tread and outer portion of the flange of the wheel. The flange f is bolted upon the ring after the substance g¹ has been rammed therein, and the pattern removed, and this flange extends inward, so as to resist any upward pressure against, and protect the lining g¹.

The bottom edge of this mould-section K is made to fit snugly upon the rabbeted upper edge of the mould-section L, so that when these two sections are brought together, there shall be no lateral displacement of either one.

The upper section J of the mould consists of a circular rim, a central hub, having a hole, i, through it, and radial spokes h h. This section J is filled with, and its bottom surface formed by the refractory substance g, which surface produces the outer face of the wheel. The object of the radial spokes h is to hold the substance g firmly within the rim, and the object of the downwardly-flaring hole a' is to allow metal to be poured into the mould-chamber, when the sections of the mould are brought together, as shown in fig. 5. The diameter of this upper section J should be slightly smaller than the inner diameter of the flange-ring f, so that as this section descends into the intermediate section K, to condense the metal in the mould, an annular space will be left between said sections J K, of sufficient size to allow a free escape of gas.

This upper section J is also constructed with bevelled or overhanging portions c c upon its upper surface, by which this section can be readily applied to a follower, I, the edges of which are also bevelled to receive between them the portions c c, as clearly shown in fig. 1.

This follower I has a flat bottom face, which covers the space between the radial spokes h of mould-section J, and thus serves as a backing, to prevent the mould-substance g from being forced upward during the act of condensing the metal in the mould.

The hole j through the centre of the follower I is designed to allow the core H' to pass freely through it, and the hole e through this follower is an ingate or pouring-hole, and which should register with the hole e', through section J, when this section is properly secured to this follower, as shown in fig. 1.

On top of the follower I is a slide, d, which is held between dovetail guides, and so arranged with refer-

ence to the ingate *e*, that when the mould is filled with melted metal, the slide can be readily driven over said ingate, so as to cut off the surplus metal and close the ingate.

The core *H'*, which leaves a hole through the central hub of the wheel when cast, consists of a core with two flanges, *b b*, secured to or formed on it at proper distance apart, between which flanges this core is coated with a refractory substance or compound, *a*, to prevent the core from being destroyed by the heat of the metal poured into the mould. This core *H'* is on the lower end of a piston-rod, *H*, the piston *G* of which works up and down in a cylinder, *F*, that is bolted strongly to the bottom of a head-plate, *C*, of the press-frame, as shown in fig. 1.

On top of the head-plate *C* is a cylinder, *D*, of considerably larger diameter than the cylinder *F*, and within this cylinder *D* works a piston, *E*, to which three rods, *F'*, are firmly secured, at regular distances apart, and at equal distances from the axis of the piston. These rods *F'* pass down through suitable stuffing-boxes applied to head *C*, and are firmly secured, at their lower ends, to the follower *I*, so that this follower will rise and descend with said piston *E*. The head-plate *C* of the press is bolted down securely upon pillars *B*, which rise perpendicularly from, and are secured firmly to the bed or foundation *A*, as shown in fig. 1.

The pistons *E* and *G*, in cylinders *D* and *F*, are moved up and down by means of hydrostatic pressure, for which purpose the said cylinders should communicate in a suitable manner with one or more hydrostatic or forcing-pumps, and should also be applied with means for allowing the fluid to escape from the chamber, on the sides of the pistons opposite to those sides upon which pressure is applied to move them.

Instead of hydrostatic-pressure to move the core and follower, these parts may be operated by means of screw-power, substantially as described in my Letters Patent of the United States, numbered 57,644.

In the selection of a protecting coating for the mould-sections and core, it is important to employ a substance or compound which will adhere firmly to the surfaces of the mould to which it is applied, and which will not expand or contract very much; also, to employ a substance or compound which will not melt and form a slag, when subjected to the intense heat of the melted metal.

The following method of preparing the mould-sections is found to be best adapted to the end in view:

The metallic portions of these sections are applied upon suitable patterns, and sharp moulding-sand rammed very hard into them. This sand is prepared by mixing with it rye meal and molasses, say about fifteen parts of the sand to one part of a mixture of rye meal and molasses. The mould-sections are then put into an oven, and baked for about twelve hours, after which they are taken out, and their sand-surfaces coated, while hot, with a solution composed of about one part of plumbago to three parts of fire-clay, made thin by adding beer to them. After coating the sand-surfaces of the mould repeatedly, and drying each coating, the surfaces are smoothed. The last coating given to the surfaces of the mould-sections should be very thick, so that it will fill up the pores in the sand, and leave solid and smooth surfaces, which will not adhere to the casting.

The operation of producing a compressed or condensed metal locomotive driving-wheel is as follows:

The mould-sections having been prepared, as shown in the drawings and above described, the two sections, *K L*, are properly adjusted in place upon the bed *A* of the press, so that their axes exactly coincide with the vertical axis of the follower *I*. Suitable guides or stops may be affixed to the top of the bed *A*, by which the proper position for the mould upon this bed can be readily found. The upper section *J* of the

mould is then slid in place on the under side of the follower *I*, and, if desired, it can be secured by pins or screws.

The cord *H'*, having been coated as above described, is then brought down through the holes which are made through the centres of the follower *I* and mould-sections *J K*, as shown in fig. 1, and held in this position by the application of pressure to the piston *G*, above the piston.

The follower *I*, with its mould-section attached, is then depressed, and the mould-section is brought within the section *K*, and held at the proper point for commencing pressure upon the metal after the mould-chamber is filled.

The ingate *e* being opened, the melted metal is poured into the mould-chamber, and this chamber filled, which will be ascertained by the ingate overflowing, when the pouring is ceased, and slide *d* forced over the ingate. Pressure is then immediately applied to the piston *E*, and continued until the metal in the mould sets, or becomes hard. When the metal has cooled sufficiently, the core *H'* and upper section *J* of the mould are raised, to allow the wheel to shrink freely and cool quickly.

It will be found, upon removing the wheel from the mould, that the shrinkage which has taken place has broken away the substance *g*, forming the upper surface of the bottom mould-section, which substance, therefore, yields, and allows the metal to contract, without liability of its cracking. For this reason, I prefer to form the interior of the three mould-sections of a refractory compound, substantially as above described. Such compound will also protect the metal parts of the mould, and thus allow of their being used repeatedly.

I do not desire to be understood as making a broad claim under this patent to a condensed metal wheel, as such a wheel has been secured to me by Letters Patent of the United States, numbered, respectively, 70,482 and 79,611. I have succeeded in practically producing a condensed metal driving-wheel for locomotive-engines, consisting of a tread, a balance, a web or spokes, a hub, and a crank. The wheels thus produced are free from pores or serious imperfections of any kind, and the metal is homogeneous in density and tenacity throughout, which results are obtained by the application of great pressure to the metal while it is in the mould, in a liquid or semi-liquid state, at the same time providing for the escape of the gases which are in the body of the metal and mould. By thus applying pressure to the metal, before it sets, it is forced to every part of the mould, and a perfect casting can be produced, with certainty, at each operation, whether steel or cast-iron be the metal used.

Having described one practical mode of producing a condensed-metal car-wheel,

What I claim as new, and desire to secure by Letters Patent, is—

1. A cast-metal locomotive driving-wheel, consisting of a tread, a web or spokes, a balance, and a hub, when such wheel has been condensed by high pressure, while in a molten state, after it has received its general final shape, substantially as described.

2. A cast-metal locomotive driving-wheel, consisting of a tread, a web or spokes, a balance, and a hub, when such wheel has been condensed by high pressure, while in a molten state, after it has received its general final shape, substantially as described.

3. A cast-metal locomotive driving-wheel, consisting of a tread, a balance, a web or spokes, a hub, and a crank, when such wheel has been condensed by high pressure, while in a molten state, after it has received its general final shape, substantially as described.
